UNITED STATES PATENT OFFICE.

JOHN B. GROSSWEGE, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

MANUALLY-OPERATED CIRCUIT-CROSSING SWITCH.

1,389,134.

Specification of Letters Patent. Patented Aug. 30, 1921.

Application filed August 15, 1918. Serial No. 249,942.

To all whom it may concern:

Be it known that I, JOHN B. GROSSWEGE, of Wilkinsburg, in the county of Allegheny and State of Pennsylvania, have invented a certain new and useful Improvement in Manually-Operated Circuit-Crossing Switches, of which improvement the following is a specification.

This invention relates to switch mechanism for electric train line circuits, particularly where an automatic electric coupling is employed having a plurality of butt contacts upon both sides of the center line for establishing electric connection between the corresponding circuits on adjoining cars. As is well known by those familiar with this art, it is customary where there are several circuits upon both sides of the center line to cross the circuits from one side to the other upon each car so that the contact terminal of each circuit at one end of the car is on the opposite side of the center from the contact terminal at the other end of the car. The cars are then reversible and either end may be connected to either end of an adjoining car. Where the electric connection between the cars is made by the ordinary jumper, the circuits are also crossed in the jumper in order to preserve the identity of circuits from car to car.

Where an automatic electric coupler of the butt type is employed, however, there is no opportunity for crossing the circuits between the cars, and for the purpose of preserving the identity of the circuits, it has been proposed to employ a switch in the car circuits near the terminals at each end of the car, and adapted in one position to connect the circuits direct, and in another position, to cross connect the circuits. Where two cars are coupled together, there are, therefore, two of these switches, one upon each car, and in order to set up the desired combination of train line circuits, it is necessary to set one of these switches to the direct position and the other to the "crossed" position.

The principal object of my invention is to provide improved switch mechanism for this purpose, and means manually operated from the side of the car for readily setting the switches to the desired positions.

In coupling cars together, the trainmen standing at one side are accustomed to per-

forming the same operation upon the devices of each car, and one of the features of my improvement comprises a manually operated connection, which is manipulated in the same direction upon each car but actuates the switch on one car to the "direct" position, and the corresponding switch on the other car to its "crossed" position, thereby establishing the proper continuity of the corresponding circuits from car to car throughout the train.

According to another feature of my invention, the switch mechanism may be manipulated from either side of the car when it is desired to return the switch to its neutral position for disconnecting and separating the cars. The switches may also be provided with contacts for closing certain local circuits upon a car, when returned to the neutral position, and this comprises another feature of my improvement.

In the accompanying drawing, Figure 1, is a circuit diagram illustrating switches and circuits for the ends of two cars coupled together according to my improvement; Fig. 2, a horizontal section of one form of switch operating mechanism; Fig. 3, a vertical transverse section taken on the line 3—3 of Figs. 2 and 4; and Fig. 4, a vertical longitudinal section of the same.

According to the diagram shown in Fig. 1, there are indicated only five car circuit wires A, B, C, D, and E, and three terminal contact points at the coupler L, M, and R, for establishing electric connection for wires A, C and E, through the train, the wires B and D, being only for local car circuits. Each car circuit wire leads to a fixed contact on the crossing switch and the coupler contacts are also connected with corresponding fixed contacts on the switch. The movable portion of the switch has a set of contact bars X, for making direct connection between the car wires and the coupler in one position, as shown at the right hand of the figure, another set of contact bars Y, for cross connecting the circuits, in the position indicated at the left hand of the figure, and a third set of contact bars Z, for closing local circuits on the respective cars when set in the intermediate or neutral position. The coupler contacts M, indicate such as may be located on the vertical center line of the coupler, which, of course, do not need to

be crossed, while the contacts L, and R, indicate those located on opposite sides of the center line and of which there are usually a large number in the actual coupler, as will 5 be readily understood.

According to my present invention, I provide manually operated means preferably extending to the sides of the car for actuating the switch to either its "direct" or 10 "crossed" position. It is also preferred that the switch should be actuated from only one side of the car to move same to the "direct" position, and from the other side of the car to move said switch to the "crossed" position. 15 One form of mechanism for this purpose is shown more particularly in Figs. 2, 3 and 4, in which the movable member or shaft 6, of the switch is provided with a plate or cam 7, rigidly attached thereto, inclosed within 20 the casing 5, and having the two pair of converging grooves or slots 8, and 9, at opposite ends. A bar or rod 10, is slidably mounted in guides 11, in the casing 5, at each side, the two bars extending to the opposite 25 sides of the car, and each having a pin 12, provided with a roller extending into the apex of the slots 8 and 9, in the neutral position, as indicated particularly in Fig. 3. The tip or point 13, of the inner face of the 30 slots is offset in each case so that when either bar is pushed in its roller pin 12, will engage below the point and be forced into the slot 8. It will thus be seen that when the bar or rod 10, at one side is pushed in the cam 35 and switch will be turned in one direction to its "direct" position, and when the bar at the other side is pushed in the cam and switch will be turned in the opposite direction to its "crossed" position. When either 40 bar is pushed in with its roller pin entering the groove 8, it will be noticed that the roller pin of the other bar will be moved into the slot 9, drawing the bar inward, as the cam turns, so that from either "direct" or 45 "crossed" position the switch may be returned to neutral position by pulling either one of the bars 10.

When the switches are symmetrically installed in the circuits at the ends of each car, 50 as indicated, and the cars are coupled up in a train, it will be seen that the push rods on one side of the train at each coupling will be alternate, that is to say, by pushing in the two bars on the adjoining cars at each coupling and on the same side of the train, one 55 switch will be shifted to the "direct" position and the other to the "crossed" position, thus establishing the proper continuity of circuits throughout the train, as will be 60 readily understood.

To release the switches for disconnecting the cars and for closing local car circuits, either one of the bars 10, at either side of the 65 train may be pulled out thus returning the cam to neutral position with contact bars Z,

connecting circuit wires C, D and B, E, for local car circuits.

In order to prevent accidental displacement of the switch, a spring actuated im- 70 positive stop 14, engaging a star wheel 15, on the shaft 6, may be employed, if desired, as shown in Fig. 4.

Having now described my invention, what I claim as new and desire to secure by Letters Patent, is:—

1. The combination with a crossing switch for car line circuits and having one position for direct connections and another position for cross connections, of a mechanical connection adapted to be operated from the side 80 of the car for shifting said switch either to its "direct" or to its "crossed" position.

2. The combination with a crossing switch for car line circuits and having one position for direct connections and another position 85 for cross connections, of manually operated mechanism actuated from one side of the car to shift said switch to its "direct" position and actuated from the other side of the car, to shift the switch to its "crossed" position. 90

3. In an electric train line system, the combination with a crossing switch for the circuits of each car, and having two positions, one for direct connection and one for cross connection, of a manually operated 95 mechanism actuated by a certain movement from the side of the car for shifting one of said switches to its "direct" position, and another manually operated mechanism actuated by the same movement at the same side 100 of the train for shifting the adjacent switch of the adjoining car to its "crossed" position.

4. The combination with a crossing switch for car line circuits and having one position for directly connecting said circuits, another position for cross-connecting said circuits, and a neutral position having contact bars for closing local car circuits. 105

5. The combination with a crossing switch 110 for car line circuits and having one position for directly connecting said circuits, another position for cross-connecting said circuits, and a neutral position having contact bars for closing local car circuits, and a manually 115 operated mechanism actuated from the sides of the car for shifting said switch from its neutral position to either its "direct" position or to its "crossed" position.

6. The combination with a crossing switch 120 for car line circuits and having one position for direct connections and another position for cross connections, of manually operated mechanism actuated from one side of the car to shift said switch to its "direct" posi- 125 tion and actuated from the other side of the car, to shift the switch to its "crossed" position, and actuated from either side of the car to return said switch to its neutral position.

7. The combination with a crossing switch for car line circuits and having one position for direct connections and another position for cross connections, of rods extending to 5 the opposite sides of the car, and mechanism operated by manipulating one rod to shift said switch to its "direct" position and operated by manipulating the other rod to shift said switch to its "crossed" position.
- 10 8. The combination with a crossing switch for car line circuits and having one position for direct connections and another position for cross connections, of push rods extending from said switch to the opposite sides of 15 the car, and mechanism operated by pushing in the rod at one side to shift said switch to its "direct" position, and operated by pushing in the other rod at the other side to shift said switch to its "crossed" position.
- 20 9. The combination with a crossing switch for car line circuits and having one position for direct connections and another position for cross connections, of push rods extending from said switch to the opposite sides of 25 the car, and mechanism operated by pushing in the rod at one side to shift said switch to its "direct" position, and operated by pushing in the other rod at the other side to shift said switch to its "crossed" position, and 30 operated by pulling out either of said rods to return said switch to its neutral position.
- 35 10. In an electric train line system, the combination with a crossing switch for the circuits of each car, and having two positions, one for direct connection and one for cross connection, of a push rod extending from said switch to the side of the car, and mechanism operated by pushing in one of the rods for shifting its switch to the "direct" position, and mechanism operated by 40 pushing in the adjacent rod of the adjoining car for shifting its switch to the "crossed" position.
11. The combination with a crossing switch for car line circuits and having one position 45 for direct connections and another position for cross connections, of a cam for operating said switch, and push rods extending to the opposite sides of the car for operating said cam.
12. The combination with a crossing switch for car line circuits and having one position for direct connections and another position for cross connections, of a cam having oppositely converging slots, and push rods having 50 pins projecting into said slots.
13. The combination with a crossing switch for car line circuits and having one position for direct connections and another position for cross connections, of a plate fixed upon the 55 shaft of said switch, push rods extending to the opposite sides of the car, and connections between the rods and the plate whereby the inward movement of one bar will turn the plate in one direction and the inward movement of the other bar will turn the plate in the opposite direction.

In testimony whereof I have hereunto set my hand.

JOHN B. GROSSWEGE.
